HERBERT J. WOODALL AND MEREDITH S. RANDALL, OF DETROIT, MICHIGAN,
ASSIGNORS TO WOODALL INDUSTRIES INCORPORATED, A CORPORATION OF MICHIGAN

VEHICLE BODY CONSTRUCTION

Application filed December 20, 1930. Serial No. 503,851.

Our invention relates to improvements in vehicle body construction and particularly to an improved interior panel for a vehicle body, and constitutes a continuation in part 5 of abandoned application Serial Number 238,515, filed December 8, 1927.

Various materials have heretofore been used for this purpose. Metal and wood have been employed and various composition materials have been used. Composition fibre board provided with a fabric, leather, or other finish, has been widely used. The composition fibre board forms a cheap panel structure but it is subject to buckling and warping due to expansion caused by the penetration of moisture.

This buckling and warping of the panel results in an unsightly interior and may cause detachment of the panel, and the problem of eliminating the same while retaining the economy afforded by the use of fibre board panels has been serious.

One object of our invention is to construct and form such a panel of inexpensive composition fibre board so that it will not buckle or warp when exposed to moisture. In attaining this object we also enhance the general appearance of the panel.

In carrying out the invention above indicated we propose to utilize a fibre board of porous cellular material which may be shaped under the action of a die-stamping machine. A fibre board composition which includes an asphaltum or other generally similar waterproofing content has been found suitable, although the broad physical characteristic of being subject to the process of stamping is the essential property. Preferably the composition board should have a relatively hard finished outer surface substantially impervious to moisture.

The panel of this material cut to size is characterized by the provision of a bead or compressed line of deformation therein 15 which separates the outer edge portion thereof from the broad central expanse. This bead, embossment, or line of demarcation is preferably formed by stamping and constitutes the gist of the invention, the real solution of the problem described.

In the formation of the bead the porous fibrous material of which the panel is composed is more closely compacted at the bead than throughout the expanse of the panel. This results in substantially arresting the 53 capillary movement of moisture within the porous fibre body of the panel from the exposed cut edge thereof toward the interior.

While the entire panel is often subjected to moisture laden atmosphere, there is a decided 60 tendency for the porous edge portions of the panel to absorb moisture far more rapidly than the relatively hard surface portion. Other attempts to solve this problem have been made, such as utilizing a waterproof 65 binding about the edge of the panel. The problem and this particular solution are illustrated in the patent to Regenstein, 1,351,-488. The moisture absorbed at the edges of the panel is that which is most effective in 70 creating deformation of the panel because it readily penetrates the interior of the panel. The compacted marginal bead in applicant's panel substantially arrests the inward capillary movement of the water, thereby preventing 75 it from reaching the broad interior expanse thereof.

Where the entire panel is exposed to moisture for any great length of time a certain amount of moisture will be absorbed through 80 the surface of the interior expanse of the panel. The amount so absorbed is, however, relatively unimportant, but here again the compacted bead plays an important part. 85 The bead functions somewhat in the manner of a hinge and the expansion of the panel is absorbed by deformation of some portion of the bead, which is more flexible than the rest of the panel.

In addition to the utilitarian features above described, the bead constitutes an effective decorative addition to the panel without necessitating the expense of securing a cord or bead to the flat surface thereof, as is often done to break the flat expanse 95 of the panel.

Other objects, advantages, and meritorious characteristics of our improved panel will more fully appear from the following 100

specification, appended claims and accompanying drawing, wherein:

Fig. 1 is a side elevation of a door panel embodying our invention.

5 Fig. 2 is a cross-sectional view taken on the line 2—2 of Fig. 1.

Fig. 3 is a side elevation of a second embodiment of our invention in a door panel.

10 Fig. 4 is a cross-sectional view taken on the line 4—4 of Fig. 3.

Fig. 5 is a fragmentary sectional view taken on the same line as Fig. 2.

Fig. 6 is a fragmentary sectional view taken on the same line as Fig. 4, and

15 Fig. 7 is a side elevation of a panel embodying our invention.

Our invention is shown as embodied in a panel for that portion of a vehicle door below the window opening but it is adapted 20 for use as an interior panel elsewhere in a vehicle. A vehicle wall is so formed as to provide frames designed to receive panels which constitute the interior trim of the body. These panels are secured in place in 25 various ways, either through fastening devices such as tacks or screws, or other connections of a similar character, or by means of flanges adapted to engage over the edge of the panel or to be engaged by it.

30 In Figs. 1 to 4 inclusive, an automobile door frame is indicated as 10. The outer metal panel is identified by the numeral 12 and our improved panel is identified generally by the numeral 14 and is secured to 35 the door frame below the window opening 16. 26 indicates a window regulator handle which extends through the panel.

Our improved panel is formed of a suitable porous flexible composition fibre board 40 having outer surfaces considerably less pervious to the taking up of moisture than the cut edges thereof. This board may be covered on one side with fabric but we prefer to provide it with a finish of its own which 45 forms an integral part thereof. The board is die stamped or embossed in such a manner as to provide a bead indicated as 18 in Figs. 1, 2 and 5, and as 20 in Figs. 3, 4 and 6, which bead preferably extends continuously 50 therearound spaced from the margin of the panel and within the frame structure to which the panel is attached, separating the outer marginal portion 22 of the panel, which is attached to the frame, from the 55 broad central interior expanse 24 of the panel.

In the formation of this bead the cellular structure of the panel is compacted and compressed along the line of the bead so that the 60 capillary passage of moisture from the edge of the panel is obstructed and the warping of the central portion of the panel is thereby inhibited. The bead not only serves to 65 obstruct the passage of moisture therebeyond and to provide a decorative feature

for the panel but it also serves to absorb expansion of the panel due to moisture which may penetrate the interior expanse of the panel through the surface, thereby preventing warping of the panel.

70 In Figs. 3, 4, and 6, the entire central portion of the panel is bumped out as shown most clearly in Fig. 4 and along the marginal portion of such upraised central expanse the cellular structure of the panel is compressed and compacted as heretofore described and for the same purposes. In Figs. 1, 2, and 5, the panel is embossed to provide an upraised rib possessing the usual characteristics of what is commonly termed a welt and the central expanse of the panel is in the same plane as the marginal portion thereof.

75 In Fig. 3 the regulator spindle opening is positioned within the central expanse enclosed by the bead and we prefer to provide about such opening a second bead which encircles the opening, obstructing the capillary passage of moisture inwardly therebeyond.

80 What we claim is:

1. In combination with a vehicle panel supporting frame, a relatively porous composition fiber board panel secured adjacent its margin to said frame, said panel having a relatively water impervious exterior surface and being substantially more pervious at its edge to ingress of moisture and provided with a compacted line extending along said edge spaced inwardly therefrom and from its point of attachment to said frame, said compacted line densified to a point substantially beyond the normal densification of the panel structure and reduced in thickness beyond the normal thickness of the panel structure without material reduction in quantity of material along said line and forming a barrier obstructing the capillary passage of moisture from the marginal portion of the panel outside of the said line to that portion of the panel within said line.

90 2. In combination with a panel supporting frame, a relatively porous composition fiber board panel secured adjacent its marginal edge to said frame by securing means extending through the panel, said panel having a relatively water impervious outer surface but being substantially more pervious to ingress of moisture at that marginal edge which is secured to the frame and provided with a compacted line extending along said edge spaced inwardly therefrom and from its point of attachment to said frame, said compacted line

100 densified to a point substantially beyond the normal densification of the panel structure forming a barrier obstructing the capillary passage of moisture from the marginal portion of the panel outside of said line to that portion within the line, said compacted line being bodily offset laterally of the normal plane of the panel forming a line of flexibility 105 permitting relative hinge like movement of

that portion of the panel on one side of said line with respect to that portion of the panel on the opposite side of said line.

3. An interior trim panel for automotive body work comprising a flexible sheet substantially impervious to moisture penetration through its face but susceptible to such penetration through the edges thereof, said panel including a portion bodily displaced from within the plane of the panel and compacted with relation to the remainder of the panel to a less thickness than such remainder of the panel, and to a point of densification substantially beyond the normal densification of the panel structure forming a barrier obstructing the capillary passage of moisture from the marginal portion of the panel outside of said line to the interior expanse of the panel within said line said portion extending substantially continuously adjacent the margin of the panel and separating the same from the broad interior expanse of said panel.

In testimony whereof, we, HERBERT J. WOODALL and MEREDITH S. RANDALL, sign this specification.

HERBERT J. WOODALL.
